UNITED STATES PATENT OFFICE.

SAMUEL K. WHITE, OF MYSTIC, CONNECTICUT, ASSIGNOR TO THE STANDARD MACHINERY COMPANY, OF SAME PLACE.

PAPER-CUTTER.

SPECIFICATION forming part of Letters Patent No. 669,869, dated March 12, 1901.

Application filed October 7, 1899, Serial No. 732,850. (No model.)

To all whom it may concern:

Be it known that I, SAMUEL K. WHITE, of Mystic, county of New London, State of Connecticut, have invented certain new and useful Improvements in Paper-Cutters; and I do hereby declare the following specification, taken in connection with the accompanying drawings, forming a part of the same, to be a full, clear, and exact description thereof.

10 The invention relates to that class of paper-cutters in which the sheets to be cut are held upon a table by a clamping-bar and are acted upon by a reciprocating cutter-blade.

Certain features of the invention relate to 15 the mechanism for regulating the pressure of the clamp upon the pile of sheets according to the resistance offered by the sheets to the passage of the cutter-blade, the construction being such that the pressure of the clamp will 20 increase as the resistance to the cutter increases. In a previous application I have shown a mechanism for accomplishing this result by operating the clamp through a movable member which is frictionally connected 25 with the clamp and regulating the friction according to the resistance to the cutter, and in said application I have claimed, broadly, this manner of operating the clamp. In the present construction the same broad invention 30 is employed, but a more simple and efficient mechanism is provided.

Further features of invention relate to the means for advancing the pile of cut sheets under the cutter, so that they may be readily 35 and conveniently removed, and consist generally in providing mechanism for automatically operating the means which thus moves the sheets, which mechanism may be thrown into operation at the will of the operator and 40 which when thrown into action automatically advances the pile of sheets under the knife without altering the setting of the back gage.

Further features of invention relate to the mechanism for starting and stopping the machine and also to the means for depressing 45 the clamping-bar at the will of the operator without operating the cutting-blade.

Other features of invention relate to combinations and constructions which will be referred to hereinafter, and particularly pointed out in the claims.

In the drawings, Figure 1 is a rear elevation of a cutter embodying all the features of the present invention in their preferred forms. Fig. 2 is a horizontal sectional view taken below the table. Fig. 3 is a side elevation. Figs. 4 and 5 are details of a part of the starting and stopping mechanism. Fig. 6 is a detail of the clutch for operating the pusher. Fig. 7 is a detail of the hand-recesses in the table. 55 Fig. 8 is a detail of the front end of the slide to which the back gage is connected. Fig. 9 is a sectional detail through the end of the guide 97 at the right of Fig. 3. Fig. 10 is a detail showing the arms 101. Fig. 11 is a detail of the means for positively starting the rod 29, and Fig. 12 is a detail of the driver for operating the clamp-bar.

Referring to the drawings in detail, the knife-bar 1 is guided in vertical slots 2, formed in the side frames 3, and is hung upon links 4, as is common in this class of cutters. The knife-bar is connected to its operating-lever 5 by a link 6 in the usual manner, and said lever is provided with a weight 7, operating 70 to rock said lever in a direction to move the cutter into its raised position and to hold said cutter in this position until the mechanism for drawing the cutter down is thrown into action. The clamping-bar 8 is suitably guided 75 in the side frames 3 and is connected at each end with a rack 9 by means of a bar 9', which is bolted to the rack and to the end of the clamping-bar. The clamping-bar is forced down upon the pile of sheets supported on the 80 table 10 by mechanism, to be described, which operates said bar through said racks, and said bar is raised by means of a weighted lever 11, which is connected with one of said racks through a link 12.

The various mechanisms of the machine are driven from a driving-shaft 13, suitably mounted in the frame and having a balance-wheel 14 secured to one end thereof. A pulley 15 is secured to the shaft 13 by being bolted to the wheel 14, and a stud 16 is secured in said pulley, upon which is mounted the loose pulley 17. The mechanism for operating the knife-lever is driven from the shaft 13 through a friction-clutch 18, one member 95 of which is secured to said shaft and the other member of which is secured to a sleeve 19,

through which said shaft passes. The sleeve 19 is suitably mounted in the side frame 3 and carries a pinion 20 at its outer end. The pinion 20 engages and drives a gear 21, connected 5 with the knife-operating shaft 22 by means to be described. The cutter-operating lever 5 is operated from the shaft 22 by means of a chain 23, which passes over a sprocket-wheel 24, secured to said shaft, and is connected 10 to the end of said lever by means of a hook 25 on said lever which engages one of the links of said chain.

The clutch 18 is thrown into operation by power-driven means, which may be thrown 15 into action at the will of the operator, and the clutch may also be thrown out of action at the will of the operator to arrest the descent of the knife and return it to its raised position. If the descent of the knife is not 20 stopped by the operator, then the clutch 18 is automatically released and the knife returned after the cut is finished. Thus the knife-bar may be accurately controlled by the operator with the expenditure of very little 25 manual power. Any suitable mechanism may be employed for thus controlling the knife-operating mechanism, and in the machine shown a preferred form of mechanism is shown for accomplishing this purpose, which in itself embodies 30 several features of invention, as will more definitely appear from the claims. As shown, the operating-arm 26 of the main clutch 18 is arranged to be engaged by a cone 27, mounted on the shaft 13 and engaged by 35 a yoke 28, secured to a reciprocating operating bar or rod 29. The rod 29 is normally held in its retracted position with the cone 27 out of engagement with arm 26 by a spring 30, interposed between frame 3 and a collar 40 on said rod, Fig. 2. The rod is advanced to engage the clutch 18 by a novel mechanism which embodies certain features of invention. This mechanism consists of a rotating member, a second member arranged to 45 be normally rotated by the engagement between said members and a cam-surface on one of said members arranged to cause a longitudinal movement of said second member when said member is held from rotation. In 50 the construction shown the rotating member consists of a collar or drum 32, secured to a shaft 33, which is continuously driven from the driving-shaft 13 by means of a gear 34, secured to said shaft 13 and engaging a gear 55, secured to shaft 33. The drum 32 is provided with a series of inclines or cams 36, which engage a series of corresponding inclines 37 on a second drum 38, loosely mounted 55 on the shaft 33 and yieldingly held against 60 the drum 32 by a sleeve 39, which surrounds shaft 33, and is formed on the end of an arm 40, projecting laterally from a sleeve 41, mounted on rod 29. The sleeve 41 is loosely mounted on rod 29 and is held in place by a 65 collar 42, pinned to said rod. The drums 32 and 38 normally rotate in unison by reason of the engagement of the cam-surfaces 36 and

37. When the rod 29 is to be advanced to engage clutch 18, the rotation of drum 38 is arrested and said drum is then moved longitudinally by the action of the cam-surfaces, and through the connections described this longitudinal movement is transmitted to rod 29. When the rod 29 is advanced, it is held 70 in its advanced position by means of a catch 75 in the form of a locking-lever 43, which engages a collar 44, secured to rod 29, and holds said rod against the tension of spring 30. The lever 43 is forced in a direction to move it into the path of the collar 44 by means of 80 a spring 45, connected at one end with an arm 46, extending down from said lever, and at the other end to an arm 47, secured to rod 29. When the rod is in its retracted position, the lever 43 is held down against the tension 85 of the spring by the collar 44, as shown in Fig. 1.

The lever 43 may be rocked to release rod 29, and thus throw the knife-operating mechanism out of operation either by the operator 90 or automatically when the cut is finished. The mechanism shown for tripping said lever 43 automatically consists of an arm or lever 49, Fig. 4, secured to the shaft 50, to which said lever is secured, and having its end arranged in the path of the knife-lever, so that when said lever has been raised to a certain position it will strike said arm and rock-shaft 50 and lever 43. The mechanism shown for tripping said lever 43 at the will of the operator will be described in connection with 100 the mechanism for arresting the rotation of drum 38.

The drum 38 is held from rotation at the desired time by means of a stop 51, formed 105 on the end of a lever 52 and arranged to be moved into the path of one or more shoulders 53 on drum 38. The shoulders 53 are formed by ribs projecting from the periphery of the drum 38, as shown in Figs. 4 and 5. The stop-lever 52 is connected by means of a link 54 with an arm 54', secured to a rock-shaft 55' at the front of the machine. A hand-lever 55 is secured to the shaft 55' within convenient reach of the operator and is normally 110 held in position to hold lever 52 away from drum 38 by a spring-pressed pin 56, the V-shaped end of which rides over the end of an arm 57, projecting from the shaft 55'. The inclines 36 and 37 are preferably of such shape 115 that the rod 29 will be advanced far enough to bring the collar beyond the end of lever 43 before said inclines have passed each other, and a cam is preferably carried by the drum 38 for disengaging the stop 51 before said inclines have passed each other, so that said inclines are always in engagement. Such a cam is shown at 58, arranged to force the stop 51 back after the drum 38 has moved a certain distance. In the construction shown the 120 lever 55 is also employed to trip the locking-lever 43 at the will of the operator in the following manner: An arm 59 is connected with the lever 52, and the end of said arm is con-

nnected by means of a link or rod 60 with the rear end of lever 43, the arrangement being such that when the lever 55 is moved in the direction of the arrow, Figs. 3 and 4, the arm 5 59 is lifted to trip the lever 43 and throw the knife-operating mechanism out of operation. When the lever 55 is moved in the opposite direction to throw the knife-operating mechanism into action, the rod 60 slides freely 10 through the end of lever 43. Means are preferably provided for positively starting the rod 29 back when the lever 43 is tripped, so that any tendency for the bar to fail to start will be overcome and the action of the spring 15 30 be made more sure and positive. A further advantage of such a means is that it enables the use of a lighter spring 30 and makes the operation of the parts more sensitive. This means preferably consists of a link 61, 20 pivoted to the end of arm 47 and provided with a slot 62, in which rides a pin 63 on the arm 46 referred to. The length of slot 62 is such that when lever 43 is rocked to release rod 29 the pin 63 will engage the end of said 25 slot and draw the rod 29 back a short distance. The engagement of the pin 63 with the end of the slot 62 does not occur until the lever 43 has moved out of engagement with the collar 44.

30 The movement of the rod 29 also throws into and out of action the mechanism for operating the clamping-bar in the following manner: The clamping-bar is operated through a shaft 64, which carries pinions 65, 35 engaging racks 9. A clutch 66 is mounted on the shaft 64, one member of said clutch being fast to said shaft and the other member being formed in a driving-gear 67. The operating-arm 68, Fig. 1, of said clutch is 40 operated by a cone 69 on the shaft 64, said cone being connected with the rod 29 by a yoke 70. When the rod 29 is advanced, the clutch 66 is engaged and the clamping-bar forced down upon the paper, and when said 45 rod is retracted said clutch is disengaged and the clamping-bar is raised by the weighted lever 11. The mechanism for operating the clamping-bar is driven by a friction driver or clutch, and the friction of said driver is increased as the resistance to the knife 50 increases, so that the paper will be clamped with a pressure proportional to the resistance to the knife. In the construction shown the friction-driver is mounted on the knife-operating shaft and consists of two friction-cones 55 71 and 72, keyed to the shaft 22, and a sleeve 73, provided with conical recesses in its ends for engaging said cones. The driver is connected with the gear 67 by means of a gear 60 74, formed on sleeve 73, and an intermediate gear 75, which engages gear 67 and gear 74. The cone 71 is pinned to the shaft 22; but the cone 72 may move longitudinally on said shaft to vary the friction between the parts 65 of the driver. The hub of cone 72 forms one part of the coupling for connecting the gear 21, heretofore described, with the shaft 22.

The other part of said coupling consists of a sleeve or drum 76, keyed to the sleeve 77, which passes through the frame 3 and forms 70 the hub of gear 21. The parts of the coupling are connected together by means of inclines 78, which form clutch-faces for causing the one part to drive the other, and also form cams tending to force the parts of the coupling away from each other, which force will increase as the resistance to the rotation of the driven part of the coupling increases. Since the knife is forced through the paper by the rotation of shaft 22, which is keyed to 80 the cone 72, and said cone is driven by the engagement of the cam-surfaces 78, said cone will be forced longitudinally with a pressure increasing as the resistance to the knife increases. The pressure between the cones 71 85 and 72 and the sleeve 73 will therefore increase with the resistance to the knife, causing increased friction between the parts of the driver which operates the clamp, and therefore forcing the clamp more firmly upon 90 the paper. There should be sufficient friction between parts of the friction-driver to bring the clamp down upon the paper in advance of the knife, and this friction may be regulated to increase or diminish the force 95 with which this initial clamping is done by adjusting the normal pressure between the parts of the friction-driver. The means shown for effecting this adjustment consists of a nut 79, which engages a screw-thread on 100 the end of shaft 22. This nut is provided with an arm 80, which carries a pin 81, arranged to engage any one of a series of holes formed in a plate 82, keyed to the shaft 22. By turning said nut the shaft 22 may be 105 moved longitudinally to draw the cones 71 and 72 and sleeve 73 more or less firmly together.

It is sometimes desirable to bring the clamp down upon the paper without throwing the 110 knife into operation, and with the present invention this is effected by power-driven mechanism which is thrown into and out of operation at the will of the operator. The preferred form of such a mechanism consists of 115 a frictional driven gearing for connecting the shaft 64 with a constantly-running shaft, such as shaft 33. As shown, the shaft 33 carries a friction-pulley 83, which is arranged to be engaged by a friction-pulley 84, carried on a lever 85, which is pivotally mounted on the shaft 64. A pinion 86 is connected with pulley 84 and engages a gear 87, secured to the shaft 64. The lever 85 may be rocked to carry the pulley 84 into engagement with pulley 83 120 by connecting the end of said lever with an arm 88, secured to a rock-shaft 89. The arm 88 is weighted to hold the pulley 84 normally away from the pulley 83. The rock-shaft 87 is provided with an arm 90, which is connected by means of a link 91 with one arm of a rock-lever 92, the other arm of which is connected by a rod 93 with a treadle 94, located 125 in a convenient position at the front of the

machine. By pressing down the treadle the operator causes the clamp to be brought onto the paper at will.

The paper to be cut is supported upon the table 10 and the size of the sheets cut is regulated by a back gage 95. After the sheets are cut they may be pushed forward under the knife, so that the operator is not obliged to put his hands under the knife in removing the paper. With the present invention the means for pushing the cut sheets under the cutter is operated by a power-driven mechanism which is thrown into operation at the will of the operator. In the machine illustrated the back gage is utilized to push forward the cut sheets, and is then returned to its former position, so that the setting or adjustment of said gage relative to the knife is not altered. It will be understood, however, that means other than the back gage may be used for this purpose without departing from the invention. In order that the gage 95 may be thus used, it is connected with a slide 96, mounted in guides 97 under the table. This slide normally stands in a definite position, with its end abutted against a stop 98 on the table. Said slide may be held against said stop by a spring 99. The back gage is set for the size of sheets to be cut by adjusting said gage relative to said slide, and the setting of said gage will not be affected, therefore, by the operation of pushing the cut sheets forward, since said slide is always returned to the same position. The gage is guided by a slot 100 in the table and is provided with depending arms 101, to which the ends of a cable 102 are secured. The cable passes around a pulley 103 at the rear of slide 96 and a drum 104 at the front end of said slide. A hand-wheel 105 is connected with drum 104, by turning which the back gage may be adjusted. A graduated tape 106 also has its ends secured to the arms 101 and passes over pulleys at the ends of the slide 96. The graduations on the tape are so arranged that the adjustment of the back gage may be read at the front of the machine. The drum 104 may be clamped to hold the back gage in its adjusted position by a clamping-handle 107. In the machine shown the power for operating the slide 96 is taken from the shaft 33 by a mechanism which in itself embodies certain features of invention. This mechanism embodies a continuously-rotating clutch member and a second clutch member which carries a cam for positively throwing the members into engagement and a second cam for throwing the members out of engagement after the clutch has made a single revolution. The continuously-rotating clutch member 108 is secured to the end of shaft 33, and the second clutch member 109 is keyed to slide on the end of a short shaft 110, mounted in a bracket 111 and arranged in line with the shaft 33. The shaft 110 has a crank-arm 112 secured to its other end, which is connected by means of a rod 113 with the slide 96.

The member 109 carries a cam 114, Fig. 6, arranged to be moved into position to engage an abutment in the form of a pin 115 when said member is moved toward the member 108. A slight movement of the member 109 brings the teeth of the clutch into engagement, so that member 109 will rotate with member 108, and the rotation of member 109 causes the cam 114 to ride against pin 115, forcing the teeth of the clutch members positively into engagement. When the member 109 has made a single revolution, a cam 116 on said member rides against a second abutment 117 and forces member 109 back and positively disengages the clutch members. It is preferred to connect cams 114 and 116 by a rib 118, which runs between the pins 115 and 117 and positively holds the clutch members in engagement during the rotation of member 109. During the single rotation of shaft 110 thus effected the crank-arm 112 acts to advance the slide 96 and return it to its normal position. The clutch member 109 is given its initial longitudinal movement by a lever 119, one end of which rides in an annular groove 120, formed in the hub of member 109. The other end of said lever is connected by means of a link 121 with an operating-lever 122, located at the front of the machine. Thus by rocking the lever 122 the operator may cause the pile of cut sheets to be quickly advanced under the knife, where they may be readily grasped by the hands and removed. The table 10 may be and preferably is provided with recesses 123 in front of the knife, over which the edge of the pile lies when advanced, so that the hands may be readily inserted under the pile in removing the same.

What I claim as my invention, and desire to secure by Letters Patent, is—

1. In a paper-cutter, the combination with the knife-bar, of mechanism for operating the same, a main shaft, devices operated therefrom for throwing said operating mechanism into operation, and means for throwing said devices into operation at will.
2. In a paper-cutter, the combination with the knife-bar, of mechanism for operating the same embodying a clutch, a main shaft, mechanism operated therefrom for engaging said clutch, and means for throwing said latter mechanism into operation at will.
3. In a paper-cutter, the combination with the knife-bar, of mechanism for operating the same, a main shaft, devices operated therefrom for throwing said operating mechanism into operation, means for throwing said devices into operation at will, and mechanism for throwing said operating mechanism out of operation automatically.
4. In a paper-cutter, the combination with the knife-bar, of mechanism for operating the same, a main shaft, devices operated therefrom for throwing said operating mechanism into operation, means for throwing said devices into operation at will, mechanism for

throwing said operating mechanism out of operation automatically, and means for throwing said operating mechanism out of operation at will.

5 5. In a paper-cutter, the combination with the knife-bar, of a clutch through which said bar is operated, a main shaft, mechanism for engaging said clutch, means operated from said shaft for throwing said mechanism into 10 operation at will, a latch for holding said clutch in engagement, and means for tripping said latch at will to release said clutch.

15 6. In a paper-cutter, the combination with the knife-bar, of a clutch through which said bar is operated, a main shaft, mechanism for engaging said clutch, means driven from said shaft for throwing said mechanism into 20 operation at will, a latch for holding said clutch in engagement, and means for automatically tripping said latch to release said clutch.

25 7. In a paper-cutter, the combination with the knife-bar, of a clutch through which said bar is operated, a rod for operating said clutch, a main shaft, mechanism operated from said shaft for advancing said rod, a latch for holding said rod advanced, means for throwing said mechanism into operation at will, and means for tripping said latch to release said clutch.

30 8. In a paper-cutter, the combination with the knife-bar, and its operating-lever, of mechanism for operating said lever, a main shaft, mechanism operated from said shaft for throwing said operating means into action, a latch for holding said mechanism in action, and means operated by the operating-lever for tripping said latch.

35 9. In a paper-cutter, the combination with the knife-bar, and operating-lever, of mechanism for operating said lever, a latch for holding said mechanism in action, a rock-shaft carrying said latch, an arm connected to said shaft and arranged in the path of said lever.

40 45 10. In a paper-cutter, the combination with the main clutch, of mechanism for operating the same comprising a rotating member, a second member driven by engagement with said rotating member, one or more cam-surfaces 50 faces on one of said members for causing a longitudinal movement of said second member when said member is held from rotation, and means for preventing the rotation of said second member at will.

55 11. In a paper-cutter, the combination with the main clutch, of mechanism for operating the same comprising a rotary member, a second member driven by engagement with said rotating member, one or more cam-surfaces 60 on one of said members for causing a longitudinal movement of said second member when said member is held from rotation, one or more shoulders on said second member, and a movable stop for engaging the same.

65 12. In a paper-cutter, the combination with the main clutch, of mechanism for operating the same comprising a rotary member, a sec-

ond member driven by engagement with said rotary member, one or more cam-surfaces on one of said members for causing a longitudinal movement of said second member when said member is held from rotation, one or more shoulders on said second member, a stop for engaging the same, and means for operating said stop at will.

70 75 13. The combination of a rotary member, a second member driven by engagement therewith, one or more cam-surfaces on one of said members for causing a longitudinal movement of said second member when said member is held from rotation, and means for preventing the rotation of said second member.

80 85 14. The combination of a rotary member, a second member driven by engagement therewith, one or more cam-surfaces on one of said members for causing a longitudinal movement of said second member when said member is held from rotation, one or more shoulders on said second member, and a movable stop for engaging the same.

90 95 15. The combination of a rotary member, a second member driven by engagement therewith, one or more cam-surfaces on one of said members for causing a longitudinal movement of said second member when said member is held from rotation, one or more shoulders on said second member, a movable stop for engaging the same, and one or more cams on said second member for disengaging said stop.

100 105 16. In a paper-cutter, the combination with a clutch-operating rod, of a spring for retracting the same, a rotating drum 32, a second drum 38, engaging inclines 36 and 37 on said drums, connections between drum 38 and said operating-rod, shoulders 53 on drum 38, a movable stop for engaging the same, a locking-lever 43 for holding said operating-rod advanced, and means for tripping said lever.

110 17. In a paper-cutter, the combination with a clutch-operating rod, a spring for retracting the same, mechanism for advancing said rod, a latch for holding said rod advanced, means for tripping said latch, and means positively starting said rod rearward.

115 18. In a paper-cutter, the combination with a clutch-operating rod 29, of mechanism for advancing the same, a spring for retracting said rod, a locking-lever 43 for holding said rod advanced, a link 61 connected with said rod, a slot 62 in said link, an arm 46 connected with said lever 43, a pin on said arm riding in said slot and arranged to engage the end of said slot and start said rod back when said lever 43 is tripped, and means for tripping said lever.

120 125 19. In a paper-cutter, the combination with the knife-bar and operating-lever, of mechanism for operating said lever, a latch for holding said mechanism in action, a rock-shaft carrying said latch, an arm carried by said rock-shaft and arranged in the path of said lever, and connections between said latch and a hand-lever.

130 20. In a paper-cutter, the combination with

the knife-bar, of mechanism for operating the same, mechanism for throwing said operating mechanism into operation embodying two rotary members connected by engaging inclines, 5 a stop-lever 52 for holding one member from rotation, a lever 43 for holding said operating mechanism in action, a lever 55 and connections between said lever and levers 52 and 43.

21. In a paper-cutter, the combination with 10 the knife-bar, of mechanism for operating the same embodying a two-part coupling or clutch, the parts of which are provided with one or more engaging inclines, a clamping-bar, operating mechanism therefor embodying 15 a friction-driver arranged to receive the direct thrust of said coupling.

22. In a paper-cutter, the combination with 20 the knife-bar, of a two-part coupling or clutch, connections between one part of said coupling and said knife-bar, means for driving the other part of said coupling, one or more cam-surfaces forming the connections between the parts of said coupling, a clamping-bar, a friction-driver for operating said 25 clamping-bar arranged to hold the parts of said coupling in engagement.

23. In a paper-cutter, the combination with 30 a knife-operating shaft, a clamping-bar, a driver therefor consisting of one or more friction-cones connected with said shaft, a sleeve on said shaft having a corresponding cone or cones, gearing between said sleeve and clamping-bar, a two-part coupling or clutch, means for rotating one of said parts, 35 means for connecting the other part to said shaft, one or more cam-surfaces connecting the parts of said coupling, and a connection between said driver and coupling whereby the parts of said driver are forced together 40 by the longitudinal movement of one of the parts of said coupling.

24. The combination with a shaft, of a friction-cone 71 secured thereto, a sleeve 73 having a corresponding conical surface, a driving-gear carried by said sleeve, a part keyed 45 to slide on said shaft and engaging said sleeve, a rotary part held from longitudinal movement, and cam-surfaces as 78 connecting the rotary and sliding parts.

50 25. The combination with a shaft, of a friction-cone 71 secured thereto, a cone 72 keyed to slide thereon, a sleeve 73 between said cones and provided with conical engaging surfaces, a driving-gear connected with said sleeve, a rotary part 76, and cam-surfaces 78 connecting part 76 and cone 72.

26. In a paper-cutter, the combination with 55 the knife-bar and clamping-bar, of a friction-driver for operating the clamping-bar, means for regulating the friction by the resistance to the knife, and a clutch for connecting said driver with and disconnecting it from said clamp.

27. In a paper-cutter, the combination with 60 the knife-bar and clamping-bar, of a friction-driver for operating the clamping-bar, means

for regulating the friction by the resistance to the knife, and means for adjusting the initial friction of said driver.

28. In a paper-cutter, the combination with 70 the knife-bar, and clamping-bar, of mechanism for operating the cutter-bar embodying a two-part coupling connection between one of said parts and the cutter-bar, cam-surfaces connecting the parts of said coupling, a friction-driver for operating the clamping-bar arranged to resist the separation of the parts of said coupling, and means for adjusting the friction of said driver. 75

29. In a paper-cutter, the combination with 80 a shaft 22 for operating the knife-bar, friction-cone 71 secured thereto, sleeve 73 having a conical surface engaging cone 71, a clamping-bar gearing between sleeve 73 and said bar, a part keyed to slide on shaft 22 and engaging 85 said sleeve, a rotary part, cam-surfaces connecting said sliding and rotary parts, and a nut on the end of shaft 22 for drawing said cones and sleeve together.

30. The combination with shaft 22, cone 71, 90 sleeve 73, cone 72 having cam-surfaces 78, drum 76 having cam-surfaces 78, sleeve 77, gear 21 connected thereto, arm 82, nut 79, arm 80, and pin 81.

31. In a paper-cutter, the combination with 95 a shaft 22 for operating the knife-bar, friction-cone 71 secured thereto, sleeve 73 having a conical surface engaging cone 71, a clamping-bar, gearing between sleeve 73 and said bar, a part keyed to slide on shaft 22 and engaging 100 said sleeve, a rotary part as 76 and cam-surfaces as 78 connecting said sliding part and part 76.

32. In a paper-cutter, the combination with 105 a shaft 22 for operating the knife-bar, friction-cone 71 secured to said shaft, friction-cone 72 keyed to slide on said shaft, a sleeve 73 between said cones and provided with conical engaging surfaces, a clamping-bar, gearing between said bar and sleeve, a rotary part as 110 76, and cam-surfaces as 78 connecting part 76 and cone 72.

33. In a paper-cutter, the combination with 115 the knife-bar, and clamping-bar, of mechanism for operating said knife-bar embodying a clutch, a friction-driver operating said clamping-bar, gearing connecting said driver and clamping-bar embodying a clutch, means for simultaneously operating said clutches, and means for regulating the friction of said 120 driver by the resistance to the knife.

34. In a paper-cutter, the combination with 125 the knife-bar and clamping-bar, of mechanism for simultaneously operating the knife-bar and clamping-bar, a main shaft, mechanism operated therefrom for bringing the clamping-bar down upon the paper independent of the operation of the knife-bar, and means for throwing said latter mechanism into action at will. 130

35. In a paper-cutter, the combination with the knife-bar, and clamping-bar, of mechan-

ism for simultaneously operating the knife-bar and clamping-bar, frictional gearing for operating said clamping-bar independently of said knife-bar, and means for throwing 5 said gearing into operation at will.

36. In a paper-cutter, the combination with the clamping-bar, of an operating-shaft connected therewith, a lever pivotally mounted thereon, a friction-pulley mounted on said lever and geared to said shaft, a constantly-running friction-pulley, and means for moving said lever at will to engage said pulleys.

37. In a paper-cutter, the combination with the knife-bar, of a back gage, means for advancing the pile of cut sheets under the knife-bar without altering the setting of the back gage, a power-operated driver for said means, and means for throwing said driver into operation at the will of the operator.

38. In a paper-cutter, the combination with the knife-bar, of a pusher for advancing the pile of cut sheets under the knife-bar, a main shaft, mechanism operated therefrom for advancing and returning said pusher, and means 25 for throwing said mechanism into action at will.

39. In a paper-cutter, the combination with the knife-bar, of a pusher for advancing the pile of cut sheets under the knife, a crank 30 connected with said pusher, a driver for operating said crank, and means for throwing said driver into action at will.

40. In a paper-cutter, the combination with the knife-bar, of a pusher for advancing the pile of cut sheets under the knife, mechanism 35 for operating said pusher comprising a rotating clutch member, a second clutch member, means for disengaging said members after a single revolution of said second member, and means for engaging said members at will.

41. In a paper-cutter, the combination with the knife-bar, of a pusher for advancing the pile of cut sheets under the knife, mechanism 45 for operating said pusher comprising a rotary clutch member, a second clutch member, a cam on said second member for disengaging said member after a single revolution,

an abutment in the path of said cam, and means for engaging said members at will. 50

42. In a paper-cutter, the combination with the knife-bar, of a pusher for advancing the pile of cut sheets under the knife mechanism for operating said pusher comprising a rotating clutch member, a second clutch member, a cam on said second member for moving said member toward said rotary member, a cam on said second member for disengaging said members, abutments in the paths of said cams, and means for moving said second 60 member toward said rotary member at will.

43. The combination of the rotary member 108, the longitudinally-movable member 109, cams 114 and 116 carried by member 109, abutments 115 and 117 and means for moving member 109 toward member 108.

44. The combination of the rotary member 108, the longitudinally-movable member 109, cams 114 and 116 carried by member 109, a web 118 connecting said cams, abutments 115 70 and 117, and means for moving member 109 toward member 108.

45. In a paper-cutter, the combination with a slide, of a back gage adjustably connected with said slide, mechanism for automatically 75 advancing said slide and returning the same to its normal position, and means for throwing said mechanism into operation at will.

46. In a paper-cutter, the combination with a slide, of a back gage adjustably connected 80 with said slide, of a clutch, means for engaging said clutch at will, means for automatically disengaging said clutch, and mechanism driven by said clutch for advancing said slide and returning the same to its normal position. 85

47. In a paper-cutter, the combination with a slide, of a back gage adjustably connected therewith, a crank connected with said slide, mechanism thrown into operation at will for 90 giving said crank a single revolution.
